Patented Mar. 21, 1922.

UNITED STATES PATENT OFFICE.

EDWARD R. BRITCHER, OF YORK, PENNSYLVANIA.

RAIL JOINT.

1,410,364.

Specification of Letters Patent. Patented Mar. 21, 1922.

Application filed January 9, 1922. Serial No. 528,063.

To all whom it may concern:

Be it known that I, EDWARD R. BRITCHER, a citizen of the United States, residing at York, in the county of York and State of Pennsylvania, have invented certain new and useful Improvements in Rail Joints, of which the following is a specification, reference being had to the accompanying drawings.

10 It is the purpose of the present invention to provide a joint for rails, whereby the adjacent ends of the rails are locked against disconnection in three different directions, for instance against movement upwardly, 15 even though the retaining spikes become loose, laterally in either direction, and also from excessive movement away from each other in alignment with the rail sections.

Another purpose is the provision of a 20 joint, wherein the fish plates and securing bolts are eliminated, which will save not only considerable expense, but also considerable labor and material.

A still further purpose is the provision 25 of a joint, which is not only locked against separable movement in the three different directions as above noted, but also the joints, which are so constructed as to permit of expansion and contraction of the rail sections 30 when united.

A further purpose is the provision of a joint, wherein the adjacent ends of the rail sections are spliced together along an inclined direction, the inclined connected ends 35 being provided with toothed surfaces, the shoulders formed thereby being so disposed and arranged as to prevent disconnection of the rail sections in the three different directions.

40 Still a further purpose is the provision of a bifurcated connection between the balls of the rails, to insure prevention of disconnection laterally in either direction.

While the design and construction at present illustrated and set forth are deemed preferable, it is obvious that as a result of a reduction of the invention to a more practical form for commercial purposes, the invention may be susceptible of changes, and 50 the right to these changes is claimed, provided they are comprehended within the scope of what is claimed.

The invention comprises further features and combination of parts, as will be herein- 55 after set forth, shown in the drawings and claimed.

In the drawings:

Figure 1 is a view in side elevation showing the adjacent ends of two rails connected by means of the improved joint; 60

Figure 2 is a detail view in side elevation of one end of one rail section;

Figure 3 is a detail view in side elevation of the end of the other rail section;

Figure 4 is a detail perspective of the 65 upper part of the rail section 1, showing the tongue 4; and

Figure 5 is a detail perspective of the upper part of the rail section 2, showing the bifurcation 22. 70

Referring to the drawings, 1 and 2 designate the adjacent end portions of two rail sections, it being noted that the end of the rail section 1 has the end of its ball 3 provided with a tongue 4. In fact the opposite 75 sides of the ball are cut away, causing to be formed angular recesses 5, which in turn cause the formation of the tongue 4. The tongue 4 and the recesses 5 extend in a vertical direction. 80

It will be noted that the rail section 1 has the lower part of its web 6 and base 7 extended, thereby providing an elongated tongue 8, which, as before stated consists of the web 6 and the base 7. 85

The web of the rail section 1 from the lower edge or corner of the tongue 4 is inclined downwardly and under the tongue 4 as shown at 9, it being obvious that the upper edge of the tongue 8 is provided with a plurality of V-shaped teeth 10 and 11, there being intervening V-shaped notches or recesses 12, for the reception of the V-shaped teeth of the end of the adjacent rail section. 90

The recess or notch 12, adjacent the tongue 4 has one of its inclined edges merging into and at right angles to the inclined edge or surface 9. The tooth 11 has its apex on a plane below the apex of the tooth 10 which has its apex on a plane below the crotch adjacent where one inclined edge of one of the recesses 12 and the inclined edge 9 come together. The tooth 11 has an inclined edge 13, which is substantially at right angles to the edge 14, which extends downwardly and under the edge 13. 95

The end of the rail section 2 is correspondingly constructed namely it has a recess 15 formed in its web and base, it being obvious that the lower portion of the web and the base are cut away, to provide for the reception of the tongue 8. The shoulders 9 and 110

24 and 14 and 15^a (which is a part of the recess 15) cooperate to prevent upward movement of the rail section 2. The cut away portion or recess (which receives the tongue 8), causes the formation of the tongue 16, the lower edge of which is provided with teeth 17 and 18, the tooth 17 being adjacent the recess or space 15, while the tooth 18 is immediately under the end of the ball of the 10 rail section 2. The provision of the teeth 17 and 18, causes the formation of a recess or cavity 19, which receives the tooth 10, while the space or recess 15 receives the tooth 11, in fact the extremity of the tongue 8. The 15 provision of the inclined face 24 causes the formation of a tooth 20, which enters the recess 12, which is partly under the tongue 4.

The end of the ball 21 of the rail section 2 has a bifurcation 22 for the reception of 20 the tongue 4, when the two rail sections are united as shown in Figure 1. It is obvious that the projections 23 caused to be formed by the bifurcation 22 enter or engage the recesses or cut away portions 5 of the rail section 1. The tooth 20 has an edge 24 merging downwardly in an inclined direction away from the ball of the rail section 2, in fact inclined downwardly under the lower end of the bifurcation 22, so that the tongue 30 4 may readily enter the bifurcation or recess 22.

It will be noted that the rail section 2 is united or connected to the rail section 1, by causing the rail section 2 to move in an inclined direction toward the tongue 8 of the rail section 1, so that the various correspondingly shaped teeth and recesses may interengage, and so that the tongue 4 of the ball of the rail section 1 may enter the recess 22 35 of the rail section 2. The interengagement of the tongue 4 with the bifurcation 22 prevents lateral movement of the rail sections in either direction, whereas the interengagement of the various teeth and recesses of the 40 tongues 8 and 16 act to prevent separable movements of the rail sections in directions 45

away from each other, while the interengagement of the inclined edges 9 and 24 prevent upward movement of the rail sections.

It will be noted that the teeth and the interengaging teeth and the recesses are so constructed and arranged, as to permit expansion and contraction of the rail sections in directions in alignment with the rails. In fact spaces 25 are provided, so as to allow 55 the rail sections to expand and contract to the climatic conditions.

It will be noted that when the spikes 26 are driven into the ties, so as to overlie the bases of the rail sections, the rail sections 60 are prevented from being detached from the ties and thereby preventing displacement of the joint between the two rail sections.

The invention having been set forth, what is claimed is:—

In a rail joint, a pair of rail sections provided with adjoining ends, said ends having overlapping tongues, said tongues having interengaging teeth and recesses formed in the web and the base of the rail sections, and disposed in a plane slightly inclined, thereby preventing separable movements of the rail sections in directions away from each other, the construction and arrangement of said interengaging teeth and recesses being such 70 as to permit of contraction and expansion of the rail sections, the adjacent ends of the balls of the adjacent rail sections having an interengaging tongue and bifurcation formed in a vertical direction, thereby preventing 75 relative lateral movement of the rail sections in either direction, the adjoining ends of said rail sections having inclined interengaging edges extending under the tongue of the ball of the rail, acting as an abutment preventing 80 upward movement of one rail section, while the toothed tongue of the other rail section prevents upward movement thereof.

In testimony whereof I hereunto affix my signature.

EDWARD R. BRITCHER.
